TELEPHONE SYSTEM

Karl L. Burgener, Chicago, Ill., assignor to Associated Electric Laboratories, Inc., Chicago, Ill., a corporation of Delaware

Application October 24, 1941, Serial No. 416,365

14 Claims. (Cl. 179—27)

The present invention relates to telephone systems and more particularly to improvements in call transfer arrangements of the character disclosed in Patent No. 2,095,712 granted October 12, 1937 to Edward S. Peterson. As explained in this patent, transfer service is especially useful to doctors, lawyers, and other professional men who are frequently absent from their offices and who do not wish to incur the expense of employing secretarial help for the purpose of answering telephone calls. It is also useful in the case of a doctor, for example, who desires to keep himself accessible to his patients at night when his office is unattended. In these and other cases, the subscribers concerned, by contracting for transfer service, are able to utilize their residence telephones for answering office calls and, accordingly, secure the equivalent of twenty-four-hour service in connection with their office telephone numbers.

It is an object of the present invention to provide an improved arrangement for giving transfer service of the character described to any subscriber of a manual system.

According to a further object of the invention, the transfer facilities are so arranged that no special handling of the calls to be transferred is required on the part of the manual office operators.

According to another object of the invention, the transfer facilities may be selectively rendered active and inactive from the substation of the subscriber for whose use the service is provided.

In accordance with still another object of the invention, provisions are made for preventing a subscriber having the transfer service from rendering his transfer facilities inactive during an interval when a transferred call is in progress.

It is another object of the invention to provide call diverting facilities of the character described, which are simple in arrangement, require a minimum of equipment, and may be readily applied to any subscriber line of a manual system with only a few changes in the wiring of the line circuit terminating the line.

The invention, both as to its organization and method of operation, together with further objects and advantages thereof, will best be understood by reference to the specification taken in connection with the accompanying drawings in which Figs. 1 and 2, when laid side by side in the order named, illustrate a manual telephone system having incorporated therein improved transfer apparatus of the character briefly referred to above.

Referring now more particularly to the drawings, the system there illustrated comprises a manual office which is equipped with the usual operator switchboard and terminates the lines serving the subscribers of the adjacent area. Three subscribers lines, 10, 11 and 12, which respectively serve the substations A, B and C, are illustrated as terminating at the operator switchboard in jacks 13, 14 and 15, respectively. The 5 numbered lines also terminate in the exchange in line circuits 16, 17 and 18, respectively, which are of identical arrangement. Thus the line circuit 16 is illustrated as comprising a line relay R210 and a cut-off relay R200, which are arranged to control a signal lamp 19 individual to the line 10. Similarly, the line circuit 17 individual to the line 11 comprises line and cut-off relays R230 and R220, respectively, which are arranged to control the signal lamp 20. The 10 details of the line circuit 18 have not been shown, but it is noted that this line circuit also includes line and cut-off relays which are arranged to control the signal lamp 21. For the purpose of setting up connections between the illustrated 15 lines and the other lines of the system, a plurality of cord circuits are provided at the operator switchboard. These cord circuits are of identical arrangement and may be of any commercial type, each thereof being equipped with answer 20 and call plugs which are respectively utilized in answering and extending calls. For example, the schematically illustrated cord circuit 25 is shown as comprising an answer plug 26 and a call plug 27. 25 For purposes of explanation, it may be assumed that the two substations A and B are the office and residence substations, respectively, of the same subscriber. It may further be assumed that 30 this subscriber desires transfer service whereby calls intended for the office substation A are automatically diverted to the residence substation B during those hours when the office substation is unattended. To this end, a transfer circuit 30 is included in the line equipment terminating the line 10 in the manual office, and a 35 key 35, of the well-known locking type, is provided at the substation A for grounding the negative line conductor 10a of the line 10. In brief, the transfer circuit 30 comprises a pair of line 40 relays R110 and R120, a cut-off relay R100, a slow-to-operate transfer relay R130, and a pair of sleeve relays R150 and R160 which are individually associated with the lines 11 and 10, respectively. The manner in which this equipment 45 is wired will be fully apparent from the following description.

lowing description of the operation of the transfer facilities. It is noted, however, that these facilities may be provided for the substation A by opening the jumper connections between the main distributing frame at which the conductors of the line 10 are terminated and the line multiple between the jacks individual to the line 10 at the operator switchboard, and connecting the transfer equipment therebetween.

In considering the operation of the system it may be assumed that the key 35 provided at the substation A is in the illustrated normal position and that the receiver of the handset provided at this substation is removed to make an outgoing call. In response to the latter operation, the transmitter and receiver of the handset are bridged across the conductors of the line 10 in the usual manner, to complete a circuit including the contacts 103 and 105 for energizing the two line relays R110 and R120 in series. In operating, the relay R110 closes its contacts 111 to complete a circuit through the contacts 121 for energizing the transfer relay R130. Concurrently with this operation, the line relay R120 opens its contacts 121 to prevent the relay R130 from remaining energized. Due to its slow-to-operate characteristic, the transfer relay R130 does not operate in response to substantially concurrent operation of the two line relays. In operating, the relay R120 also closes its contacts 122 to complete a circuit including the resistor 123 and the contacts 201 and 202 for energizing the line relay R210. In operating, the relay R210 closes its contacts 211 to complete an obvious circuit for energizing the lamp 19. The illuminated condition of this lamp serves to signal the operator in attendance at the operator switchboard in the manual office that a call has been extended to the jack 13, which should be disposed of.

To answer the call, the operator inserts the answer plug 26 of the cord circuit 25 in the jack 13, and in so doing connects negative battery potential through the sleeve contact 26c of this plug to the sleeve contact 13c of the jack 13, thereby to energize the sleeve relay R160. More specifically, the operating circuit for the relay R160 extends from ground by way of the winding of this relay, the contacts 139 and 152 in parallel, the sleeve contacts 13c and 26c of the jack 13 and the plug 26, respectively, and the winding of the sleeve relay in the cord circuit 25, to battery. When thus energized the relay R160 operates and opens its contacts 161 to interrupt one branch of the circuit for energizing the sleeve relay R150. At its contacts 162, the relay R160 prepares a path for impressing negative battery potential upon the sleeve contact 14c of the jack 14 terminating the line 11. At its contacts 163, the relay R160 closes an obvious circuit for energizing the cut-off relay R100.

In operating, the relay R100 closes its contacts 101 to prepare a locking circuit for the transfer relay R130. At its contacts 102 and 104, the relay R100 connects the negative and positive conductors of the line 10 through the contacts 135 and 137 to the engaged tip and ring contacts of the jack 13 and the answer plug 26. At its contacts 103 and 105, the relay R100 disconnects the line relays R110 and R120 from the conductors of the line 10, causing both of these relays to restore. In releasing, the relay R110 opens its contacts 111 to interrupt the incomplete operating circuit for the transfer relay R130. The relay R120, upon restoring, closes its contacts 121 to reprepare the operating circuit for the trans-

fer relay R130, and opens its contacts 122 to interrupt the path over which the resistor 123 is bridged across the tip and ring contacts of the jack 13.

5 In operating, the cut-off relay R100 also closes its contacts 106 to complete a circuit for energizing the cut-off relay R200, this circuit extending from ground by way of the winding of R200, the contacts 141 and 106, and the resistor 107 to battery. In operating, the relay R200 opens its contacts 202 to disconnect the positive side of the line 10 from ground. At its contacts 201, the relay R200 opens another point in the operating circuit for the line relay R210. In releasing, the latter relay opens its contacts 211 to deenergize the signal lamp 19 in an obvious manner.

After the call has been answered by the operator in the manner just explained, and the desired directory number is transmitted to this operator from the calling party at the substation A, the call may be extended through the call plug 27 to any desired substation of the system. For example, the call plug 27 may be inserted in the jack 15 to establish a connection to the line 12, after which the ringing key of the cord circuit 25 may be operated to transmit ringing current over the line 12 for the purpose of energizing the ringer conventionally provided at the called substation C. When a connection is thus established to the line 12, the cut-off relay of the line circuit 18 operates to disconnect the windings of its associated line relay from the conductors of the line 12. When the call is answered at the called substation, the operator handling the call in the manual office may retire from the connection and rely upon the supervisory lamps forming a part of the cord circuit 25 to indicate the condition of the connection. When these lamps produce an indication that the connection has been released at the calling and called substations A and C, respectively, the operator may clear out the connection by withdrawing the answer plug 26 from the jack 13 and the call plug 27 from the jack 15. In response to the latter operation the line circuit 18 is restored to normal in the usual manner. When the answer plug 26 is withdrawn from the jack 13, the sleeve contact 13c of this jack is disconnected from the negative terminal of the exchange battery to deenergize the sleeve relay R160. In releasing, this relay opens its contacts 163 to deenergize the cut-off relay R100. The latter relay, upon restoring, opens its contacts 106 to deenergize the cut-off relay R200 of the line circuit 16. Thus all of the equipment utilized in setting up the connection is restored to normal.

In considering the manner in which calls may be routed to the substation A at a time when the transfer circuit 30 is inactive, it may be assumed that a call originated at the substation C is extended to the operator headset through the cord circuit 25, and that the substation A is desired by the calling party. To complete the connection the operator handling the call inserts the call plug 27 in the jack 13 and, incident thereto, connects the sleeve contact 13c of the jack 13 to the negative terminal of the exchange battery through the sleeve contact 27c of the plug 27, whereby the above-traced operating circuit for the sleeve relay R160 is completed. In operating, the relay R160 causes the sequential operation of the two relays R100 and R200 in the manner previously explained, whereby the operating circuit for the line relay R210 is interrupted and the conductors of the line 10 are connected through the contacts 102, 104, 135 and 137 to the

connected tip and ring contacts of the jack 13 and the plug 27. After these relay operations are completed, the operator may, by operating the ring key of the cord circuit 25, transmit ringing current over the line 10 for the purpose of energizing the ringer provided at the substation A. The manner in which a connection of this character is released will be clearly apparent from the above explanation.

The manner in which incoming and outgoing calls involving the residence substation B are handled by the operators in attendance at the switchboard in the manual office, is entirely conventional. In this regard it will be noted that when either the answer plug 26 or the call plug 27 of the cord circuit 25, for example, is inserted in the jack 14, the sleeve contact 14c of this jack is connected to the negative terminal of the exchange battery to complete a circuit through the parallel-connected contacts 131 and 161 for energizing the sleeve relay R150. In the event the line 10 is occupied with a call at the time a call is routed from or extended to the line 11, the sleeve relay R160 is operated so that the circuit for energizing the sleeve relay R150 only extends through the contacts 131. Regardless of this fact, however, the sleeve relay R150 operates and closes its contacts 151 to prepare a path for connecting the sleeve contact 13c of the jack 13 to the negative terminal of the exchange battery. At its contacts 152, the relay R150 opens one of the parallel branches of the above-traced operating circuit for the sleeve relay R160. It will be noted, however, that this operation does not interrupt the operating circuit for the sleeve relay R160 so long as the transfer relay R130 occupies its restored position. At its contacts 153, the relay R150 completes a circuit including the resistor 154 for energizing the cut-off relay R220. In operating, the relay R220 opens its contacts 221 and 222 to interrupt two points in the operating circuit for the line relay R230. In case the call in progress is an outgoing call originated at the substation B, the line relay R230 is deenergized and opens its contacts 231 to deenergize the signal lamp 20, incident to the operation of the cut-off relay R220. On the other hand, if the call in progress is incoming to the substation B, the operation of the relay R220 prevents the subsequent operation of the line relay R230 when the call is answered at the substation B. Obviously the operated sleeve and cut-off relays R150 and R220 are deenergized and restore when the plug of the cord circuit 25, utilized in handling the connection, is withdrawn from the jack 14 to disconnect the sleeve contact 14c thereof from the negative terminal of the exchange battery.

In considering the manner in which calls are diverted to the substation B at a time when the office substation A is unattended, it may be assumed that the subscriber at the latter substation actuates the key 35 to its off-normal position wherein the line conductor 16a is connected to ground. Incident to this operation a circuit including the contacts 103 and the negative line conductor 16a is completed for energizing the line relay R110. This relay remains in its operated position until the key 35 is manually restored to normal. It will be noted that if an outgoing call is originated at the office substation A, with the key 35 in its off-normal position, the line relay R120 is short-circuited over a path which includes the contacts of this key, the bridging path between the conductors of the line 10, the positive side of this line, and the contacts

105. Accordingly, with the key 35 operated, calls cannot be extended from the substation A.

Upon operating in response to the operation of the key 35 to its off-normal position, the line relay R110 closes its contacts 111 to complete the above-mentioned circuit through the contacts 121 for energizing the slow-to-operate transfer relay R130. In operating, the relay R130 closes its contacts 133 to prepare the above-mentioned locking circuit for itself. At its contacts 131 and 139, the relay R130 opens the above-described branches of the respective operating circuits for the two sleeve relays R150 and R160. By virtue of this operation, only one of the two sleeve relays can subsequently be operated at any given time. At its contacts 132 and 138, the relay R130 prepares the above-mentioned paths for impressing negative battery potential upon the sleeve contacts 13c and 14c of the jacks 13 and 14, respectively. At its contacts 141, the relay R130 opens a point in the previously traced operating circuit for the cut-off relay R200 of the line circuit 16. At its contacts 140, the relay R130 prepares an alternative circuit for energizing the cut-off relay R220 of the line circuit 17. At its contacts 135 and 137, the relay R130 opens the paths over which the tip and ring contacts of the jack 13, individual to the line 10, may be connected to the conductors of this line. At its contacts 134 and 136, the relay R130 connects the tip and ring contacts of the jack 13 to the conductors of the line 11 and the tip and ring contacts of the jack 14.

Following the operations just described, the transfer circuit 39 is actively conditioned to automatically divert to the substation B calls which are extended to the line 10 through the cord circuit 25, for example, and the jack 13 individual to the line 10. Thus, if the call plug 27 of the cord circuit 25, for example, is inserted in the jack 13 during an interval when the transfer relay R130 is operated, the tip and ring conductors of the cord circuit are connected through the tip and ring contacts of the jack 13 and the contacts 134 and 136 to the negative and positive conductors of the line 11. Moreover, negative battery potential is impressed upon the sleeve contact 13c of the jack 13 to energize the sleeve relay R160 in a circuit which now only includes the contacts 152. In operating, the relay R160 closes its contacts 163 to energize the cut-off relay R100. At its contacts 161, the relay R160 opens the only branch of the circuit over which the sleeve relay R150 may be energized. At its contacts 162, the relay R160 connects the sleeve contact 14c of the jack 14 to the negative terminal of the exchange battery through the contacts 132 and the resistor 124. The completion of this path serves to provide an indication that the line 11 is busy. Thus if another operator should attempt to insert a call plug into the jack 14, the negative battery potential encountered on the sleeve contact 14c by the sleeve contact of the call plug in use, causes the supervisory equipment of the cord circuit in use to produce an indication that the line 11 is busy. Thus the operator handling the second call is prevented from intruding on the diverted call.

In this case the cut-off relay R100, upon operating, closes its contacts 106 to complete the above-mentioned alternative operating circuit for the cut-off relay R220, this circuit extending from ground by way of the winding of R220, the contacts 140 and 106, and the resistor 107 to battery. In operating, the relay R220 performs the

functions described above. At its contacts 101, the relay R100 completes the above-mentioned locking circuit for the transfer relay R130. At its contacts 103, the relay R100 opens the circuit over which the line relay R110 is being held energized. The relay R110 now restores and opens its contacts 111 to interrupt the operating circuit for the transfer relay R130.

From the above explanation it will be noted that the cut-off relay R100 performs the function of preventing the transfer circuit 30 from being rendered inactive under the control of the subscriber at the substation A during a period when the line 11 is occupied with a call which has been diverted thereto from the line 10. In this regard it will be understood that the cut-off relay R100 is held in its operated position for the duration of the call under consideration. With this relay operated, the transfer relay R130 is locked up through the contacts 133 and 101. Further, the operating circuit for the line relay R110 is held open at the contacts 103 so that a subscriber at the office substation A can exercise no control thereover. The purpose of this arrangement is to prevent a call which has been diverted to the line 11 from the line 10 from being interrupted before it is terminated in the normal manner.

After the diverted call has been extended to the line 11 in the manner just explained, and the relays R160, R100 and R220 have operated, the operator handling the call may actuate the ring key of the cord circuit 25 to project ringing current through the contacts 134 and 136 and over the line 11 to energize the ringer provided at the residence substation B. It will be apparent that when the call is answered a talking circuit is set up between the cord circuit 25 and the substation equipment at the residence substation which includes the conductors of the line 11, the contacts 134 and 136 of the transfer relay R130, and the engaged tip and ring contacts of the jack 13 and the call plug 27.

When the supervisory equipment of the cord circuit 25 indicates to the operator handling the call that the connection has been released at both the calling and called substations, the operator may clear out the connection by withdrawing the answer plug 26 from the jack terminating the calling line and the call plug 27 from the jack 13. Incident to the latter operation the sleeve contact 13c is disconnected from the negative terminal of the exchange battery to deenergize the sleeve relay R160. This relay, in restoring, causes the sequential release of the two cut-off relays R100 and R220 in an obvious manner. The relay R100, upon restoring, first closes its contacts 103 to again energize the line relay R110, and then opens its contacts 101 to interrupt the locking circuit for the transfer relay R130. In operating, the relay R110 recloses its contacts 111 to again complete the operating circuit for the transfer relay. Thus the transfer relay R130 is prevented from restoring in response to the release of the cut-off relay R100, assuming that the transfer key 35 has not been operated to its normal position during the period of the diverted call. Following the release of the relays R160, R100 and R220 and the reoperation of the line relay R110, the transfer equipment is restored to its normal active setting.

If a connection is set up through the cord circuit 25 between the line 11 and another line of the system at a time when the transfer circuit

30 is conditioned for operation the sleeve relay R150 is energized from the cord circuit when the call or answer plug of the cord circuit is inserted in the jack 14. In operating, the relay R150 closes its contacts 153 to complete the previously traced operating circuit for the cut-off relay R220, and opens its contacts 152 to interrupt the only branch of the circuit over which the sleeve relay R160 may be energized. Thus the relay R160 is rendered non-responsive to the insertion of a call or answer plug in the jack 13. At its contacts 151, the relay R150 completes the previously mentioned path for impressing negative battery potential upon the sleeve contact 13c of the jack 13, this path extending from the negative terminal of the exchange battery by way of the resistor 124 and the contacts 132, 138 and 151. The purpose of completing this path is to provide an indication that the line associated with the jack 13 is occupied with a call. Thus, if another operator inserts a call plug in this jack at a time when the sleeve relay R150 and the transfer relay R130 are operated, the supervisory equipment of the cord circuit in use functions to provide an indication that the line connected to the jack 13 is busy. When the connection involving the line 11 is cleared out at the operator switchboard, negative battery potential is removed from the sleeve contact 14c of the jack 14 to cause the sequential release of the sleeve relay R150 and the cut-off relay R220. Thus the transfer circuit 30 is restored to its normal active setting.

From the above explanation it will be understood that the transfer circuit may be restored to its inactive setting under the control of the subscriber at the office substation A at any time except when a call diverted from the jack 13 to the line 11 is in progress. Thus it will be noted that the operation of the sleeve relay R150 which occurs incident to the setting up of a connection through the jack 14 to the line 11, does not cause the operation of the cut-off relay R100. So long as this cut-off relay occupies its restored position the transfer circuit 30 may be released. To this end the transfer key 35 is restored to its normal position to deenergize the line relay R110. In releasing, the relay R110 opens its contacts 111 to deenergize the transfer relay R130. Following the release of the latter relay, the transfer circuit is rendered inactive to divert calls from the jack 13 to the line 11. It will be noted that after the transfer relay R130 is released by restoring the transfer key 35 to normal, an outgoing call may immediately be initiated at the office substation A without in any way interfering with a connection which may exist between the line 11 and another line of the system over a route which includes the jack 14.

While one embodiment of the invention has been disclosed, it will be understood that various modifications may be made therein which are within the true spirit and scope of the invention.

What is claimed is:

1. In a telephone system which includes a manual office, an office line, a residence line, office and residence substations respectively served by said office and residence lines, jacks terminating said lines in said office, means including an operator cord circuit for setting up connections between said lines and the other lines of the system, and means in said manual office selectively controllable over one of said lines from the substation served by said one line for diverting to the other of said lines calls which have

been extended to said one line through said cord circuit and the jack terminating said one line.

2. In a telephone system which includes a manual office, first and second substation lines, jacks and line circuits terminating said lines in said manual office, means including an operator cord circuit for setting up connections between said lines and the other lines of the system, means at the substation served by the first of said lines adapted for sustained operation to indicate that said substation is unattended, and means in the line circuit terminating said first line and controlled by the operation of said last-named means for automatically diverting to said second line calls which have been extended to said first line through said cord circuit and the jack terminating said first line.

3. In a telephone system including an operator switchboard, a pair of substation lines, jacks terminating said lines at said switchboard, means including an operator cord circuit for setting up connections between said lines and the other lines of the system, means for automatically diverting to a first of said substation lines calls which have been extended to the second of said substation lines through said cord circuit and the jack terminating said second line, means for rendering said call diverting means inactive, and means for preventing said last-named means from rendering said call diverting means inactive at a time when said first line is occupied with an incoming call which has been diverted thereto from said second line.

4. In a telephone system including an operator switchboard, a pair of substation lines, jacks terminating said lines at said switchboard, means including an operator cord circuit for setting up connections between said lines and the other lines of the system, means for automatically diverting to a first of said substation lines calls which have been extended to the second of said substation lines through said cord circuit and the jack terminating said second line, means for rendering said call diverting means inactive, and means controlled from said cord circuit through the jack terminating said second line for preventing said last-named means from rendering said call diverting means inactive at a time when said first line is occupied with a call which has been diverted thereto from said second line.

5. In a telephone system which includes a manual office, an office line, a residence line, office and residence substations respectively served by said office and residence lines, jacks terminating said lines in said manual office, means including an operator cord circuit for setting up connections between said lines and the other lines of the system, means for automatically diverting to one of said lines calls which have been extended to the other of said lines through said cord circuit and the jack terminating said other line, means controllable from the substation served by said other line for rendering said call diverting means inactive, and means for preventing said last-named means from rendering said call diverting means inactive at a time when said one line is occupied with an incoming call which has been diverted thereto from said other line.

6. In a telephone system which includes a manual office, an office line, a residence line, office and residence substations respectively served by said office and residence lines, jacks terminating said lines in said manual office, means including an operator cord circuit for set-

ting up connections between said lines and the other lines of the system, means for automatically diverting to said residence line calls which have been extended to said office line through said cord circuit and the jack terminating said office line, means controllable from said office substation over one side of said office line for rendering said call diverting means inactive, and means for preventing said last-named means from rendering said call diverting means inactive at a time when said residence line is occupied with an incoming call which has been diverted thereto from said office line.

7. In a telephone system which includes a manual office, an office line, a residence line, office and residence substations respectively served by said office and residence lines, jacks terminating said lines in said manual office, means including an operator cord circuit for setting up connections between said lines and the other lines of the system, means for automatically diverting to said residence line calls which have been extended to said office line through said cord circuit and the jack terminating said office line, means controllable from said office substation over one side of said office line for rendering said call diverting means inactive, and means controlled from said cord circuit through the jack terminating said office line for preventing said last-named means from rendering said call diverting means inactive at a time when said residence line is occupied with an incoming call which has been diverted thereto from said office line.

8. In a telephone system, a substation line, a transfer relay for diverting calls intended for said line to another line of the system, two line relays normally bridged across said substation line, one of said relays being operative in response to the grounding of said substation line at the station served by said substation line and both of said relays being operative in response to the bridging of said substation line at said station, a circuit for said transfer relay jointly controlled by said line relays, and means responsive to a call incoming to said substation line at a time when said transfer relay is operated for disconnecting said line relays from said substation line.

9. In a telephone system a substation line, a transfer relay for diverting calls intended for said line to another line of the system, two line relays normally bridged across said substation line, one of said relays being operative in response to the grounding of said substation line at the station served by said substation line and both of said relays being operative in response to the bridging of said substation line at said station, a circuit for said transfer relay jointly controlled by said line relays, means responsive to a call incoming to said substation line at a time when said transfer relay is operated for disconnecting said line relays from said substation line, and means operative when said other line is occupied with an outgoing call or a call routed directly thereto for preventing the operation of said last-named means and for providing an indication that said substation line is busy.

10. In a telephone system which includes an operator switchboard, a pair of substation lines, jacks terminating said substation lines at said switchboard and each including a control contact, means including an operator cord circuit for setting up connections between said lines and the other lines of the system, means for auto-

matically diverting to one of said lines calls which have been extended to the other of said lines through said cord circuit and the jack terminating said other line, means controllable over said other line for selectively rendering said call diverting means active and inactive, a relay controlled over the control contact of the jack terminating said other line and operative each time a call is extended to said other line through said cord circuit, and means responsive to the operation of said relay for rendering said last named means non-controllable over said other line.

11. In a telephone system which includes an operator switchboard, a pair of substation lines, jacks terminating said substation lines at said switchboard and each including a control contact, means including an operator cord circuit for setting up connections between said lines and the other lines of the system, means for automatically diverting to one of said lines calls which have been extended to the other of said lines through said cord circuit and the jack terminating said other line, means controllable over said other line for selectively rendering said call diverting means active and inactive, a relay controlled over the control contact of the jack terminating said other line and operative each time a call is extended to said other line through said cord circuit, and means responsive to the operation of said relay with said call diverting means active for rendering said last-named means non-controllable over said other line and for providing an indication that said one line is busy.

12. In a telephone system which includes an operator switchboard, a pair of substation lines, jacks terminating said substation lines at said switchboard and each including a control contact, means including an operator cord circuit for setting up connections between said lines and the other lines of the system, means for automatically diverting to one of said lines calls which have been extended to the other of said lines through said cord circuit and the jack terminating said other line, means controllable over said other line for selectively rendering said call diverting means active and inactive, a relay controlled over the control contact of the jack terminating said other line and operative each time a call is extended to said other line through said cord circuit, means responsive to the operation of said relay for rendering said last-named means non-controllable over said other line, a

second relay controlled over the control contact of the jack terminating said one line and operative each time said one line is occupied with a call extended through the jack terminating said one line, and means responsive to the operation of said second relay for preventing the operation of said first-named relay.

13. In a telephone system which includes an operator switchboard, a pair of substation lines, 10 jacks terminating said substation lines at said switchboard and each including a sleeve contact, sleeve relays individually controlled over said sleeve contacts and each operative each time a connection is extended through the associated jack, means including an operator cord circuit 15 for setting up connections between said lines and the other lines of the system, means for automatically diverting to one of said lines calls which have been extended to the other of said lines through said cord circuit and the jack terminating said other line, means for selectively rendering said call diverting means active and inactive, and means responsive to the operation of either of said sleeve relays at a time when said 20 call diverting means is active for providing an indication that the non-associated line is busy.
14. In a telephone system which includes an operator switchboard, a pair of substation lines, jacks terminating said substation lines at said 30 switchboard and each including a sleeve contact, sleeve relays individually controlled over said sleeve contacts and each operative each time a connection is extended through the associated jack, means including an operator cord circuit 35 for setting up connections between said lines and the other lines of the system, means for automatically diverting to one of said lines calls which have been extended to the other of said lines through said cord circuit and the jack terminating said other line, means controllable over 40 said other line for selectively rendering said call diverting means active and inactive, means responsive to the operation of the sleeve relay individual to said other line at a time when said call diverting means is active for rendering said last-named means non-controllable over said other line, and means responsive to the operation of either of said sleeve relays at a time when 45 said call diverting means is active for providing an indication that the non-associated line is busy.

KARL L. BURGENER.
